UNITED STATES PATENT OFFICE.

WILLIAM E. BUDD, OF ELIZABETH, NEW JERSEY.

ANTISKIDDING ATTACHMENT FOR TIRES.

1,080,259.

Specification of Letters Patent.

Patented Dec. 2, 1913.

Application filed January 29, 1913. Serial No. 744,958.

To all whom it may concern:

Be it known that I, WILLIAM E. BUDD, a citizen of the United States, residing at Elizabeth, in the county of Union and State 5 of New Jersey, have invented certain new and useful Improvements in Antiskidding Attachments for Tires, of which the following is a specification, reference being had to the accompanying drawings.

10 This invention comprehends certain new and useful improvements in anti-skidding attachments for the tires of automobile, motor truck, or other vehicle wheels, and the invention has for its primary object a simple, durable and efficient construction of device of this character, the parts of which are so arranged and adapted to be attached to the wheel that each part will be practically independent of all of the others, whereby 15 any desired number of chains and their correlated parts may be used according to the particular requirements of the case, and whereby when one chain or its attached devices become broken, that will not affect in 20 any wise the others.

The invention also has for its object an attachment of this character which may be easily secured to the wheel, which will be securely held in position as long as desired 25 without liability of accidental displacement, and which may be easily removed or stripped from the wheel when not required. And the invention also aims to generally improve devices of this class so as to render 30 them more useful and commercially desirable.

With these and other objects in view, as will more fully appear as the description proceeds, the invention consists in certain 35 constructions, arrangements and combinations of the parts that I shall hereinafter fully describe and claim.

For a full understanding of the invention, reference is to be had to the following description and accompanying drawing, in which:

Figure 1, is a side elevation of a wheel showing my attachment applied thereto; Fig. 2, is a transverse sectional view through 50 the tire, rim and felly, showing one of the attachments; Fig. 3, is a detail perspective view of one of the studs or projections hereinafter specifically referred to; and Fig. 4, is a detail view of one of the clamping bars.

55 Corresponding and like parts are referred to in the following description and desig-

nated in the accompanying drawing by like reference characters.

Each of my improved anti-skidding attachments comprises a flexible tread member 1 which is preferably composed of any desired number of connected links, as shown, the end links being preferably of brass, while the intermediate or remaining links are of steel. The end links, designated 2, 60 are engaged in apertures 3 that are formed in angular anchoring bars or fasteners 4 that are preferably formed of spring steel or some other resilient metal or material. Preferably, these bars or fasteners 4 are identical in structure, whereby they are interchangeable and can be cheaply made by the operation of a single die. The apertures 3 are formed in the bars or fasteners 4 near one extremity thereof and each bar 4 is also 65 formed in its opposite end with a plurality of openings 5 arranged in a longitudinal series to provide for adjusting the anti-skidding device to tires of different sizes.

6 designates projections which, in the 70 present instance, are in the form of studs secured in any desired way to the felly 7 of the wheel and projecting inward in a radial direction therefrom. In the present instance, these studs are provided at one end 75 with screw threaded portions, whereby they may be easily inserted into the felly, but it is to be understood that the invention is not limited in this regard, but that any manner of securing the studs in place may be employed. Preferably, there is one of these 80 studs 6 between every two spokes of the wheel, although it is to be understood that the invention is not limited in that regard 85 either.

The studs 6, as will be clearly seen from the drawing, have their inwardly projecting ends formed with somewhat rounded and ornamental heads 8 (although the heads may be omitted), and these heads, as is manifest, produce annular shoulders 9, the studs tapering toward the shoulders from the main portion of the studs contiguous to the inner edge of the felly. Preferably, the 90 studs are encircled by washers 10 of felt, 95 leather or the like.

From the foregoing description in connection with the accompanying drawing, it will be understood that in the practical application of my invention, the wheel is 100 equipped with a series of the studs 6, and whenever it is desired to guard against any 105

skidding or slipping of the wheel, the necessary number of chains are applied, according to the requirements of the case or the conditions at hand. In applying a chain, it is passed transversely over the tread of the tire and the bars or fasteners 4 are brought down over the side faces of the rim and felly and are slipped one after the other over the inwardly projecting head 8 of a stud 6, the stud being received in any of the openings 5, according to the width or diameter of the tire and its felly and rim, adjustment of the parts being thereby taken care of. Owing to the spring characteristics of the bars or fasteners 4, they will be securely held in place, while at the same time, the tread members 1 will not necessarily be stretched taut across the tire, in which event, they might injure it, neither is the paint or enamel of the felly injured or marred in any way by the use of my attachments, as the bars or fasteners 4 will not engage and rub upon the side faces of the felly.

It will thus be seen that I have provided a very simple anti-skidding attachment for tires, one that can be cheaply manufactured and one which possesses to a marked degree, the advantageous characteristic of capability of quick attachment and detachment. Furthermore, as each tread member 1 with its bars or fasteners 4 is separate from and independent of all of the other bars and their connected tread members, it is obvious that any desired number of the devices may be used according to the condition of the ground over which the vehicle is passing, and that should one of the devices become broken, that will not affect any of the others and the broken one can be repaired or replaced at a small cost, whereas with the ordinary tire armor or anti-skidding chain in which the transversely extending tread members are all connected together by circumferentially extending chains, it is quite common to lose the entire device should any link become broken.

It is to be observed that the outer end portions 4' of the bars or fasteners 4 are flexed upwardly normally at substantially right angles and that the bend 4^a of such flexure is positioned relatively to the post 6 a distance less than the distance from the plane occupied by the post 6 to the outer edge of the felly 7 with which the flexed portion 4' is adapted to contact, it being understood that in referring to the felly 7, the rim secured thereto is included. As the bar or fastener 4 is produced from spring metal it will be obvious that the flexed portion 4' will be distended when the fastener is placed in operative position and thus creating a frictional means whereby the bar or fastener

4 will be prevented from displacement as a resultant binding will be created between the bar or fastener 4 and the post 6. If from any cause the bars or fasteners 4 may be caused to move outwardly of the post 6, it will be understood that the resiliency possessed by the bars or fasteners 4 will cause the same to spring in contact with the head 8 whereby the bars or fasteners are effectually held against displacement. By using washers 10 on the studs 6, it is obvious that the overlapped ends of the anchoring bars or fasteners will not rest directly upon the felly and this feature also tends to preclude any liability of marring the paint.

While the accompanying drawing illustrates what I believe to be the preferred embodiment of my invention, it is to be understood that the invention is not limited here-to, but that various changes may be made in the construction, arrangement and proportions of the parts without departing from the scope of the invention, as defined in the appended claims.

What I claim is:—

1. In combination with the felly of a wheel, a post inwardly directed from the felly, and a normally substantially right angular chain fastener of spring metal provided with a perforation in one of its portions to surround the post, the opposite portion of the fastener being adapted to frictionally engage the felly, the distance between the aperture of the fastener in engagement with the post and the bend thereof being less than the distance between the post and the edge surface of the felly with which the fastener contacts.

2. In combination with the felly of a wheel, a post inwardly directed from the felly, and a normally substantially right angular chain fastener of spring metal provided with a perforation in one of its portions to surround the post, the opposite portion of the fastener being adapted to frictionally engage the felly, the distance between the aperture of the fastener in engagement with the post and the bend thereof being less than the distance between the post and the edge surface of the felly with which the fastener contacts, the free end portion of the post being provided with a head insertible through the aperture of the fastener and serving as a positive means whereby the fastener may be held against displacement from the post.

In testimony whereof I hereunto affix my signature in the presence of two witnesses.

WILLIAM E. BUDD.
